CLAIM

The ornamental design for a medical garment, as shown and described.

DESCRIPTION

FIG. 1 is a front elevational view of a medical garment showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a perspective view thereof;

FIG. 8 is a rear perspective view showing the present invention with the a pair of covers removed;

FIG. 9 is a cutaway front right perspective view thereof, showing the rear interior of the present invention;

FIG. 10 is a cutaway front left perspective view thereof; and,

FIG. 11 is a cutaway rear perspective view thereof, showing the front interior of the present invention.

The broken line showing of a collar and fasteners is included for the purpose of illustrating environmental structure and forms no part of the claimed design.
